AUTOMATIC ARCH SUPPORT FOR SHOES

Filed Nov. 5, 1926

Inventor:

Horace C. Mayers;

Robert W. Fawcett,

Attorney.

Patented Dec. 6, 1927.

1,652,034

UNITED STATES PATENT OFFICE.

HORACE C. MAYERS, OF CLEVELAND, OHIO, ASSIGNOR OF ONE-HALF TO LEON F. MONTGOMERY, OF PORTLAND, INDIANA.

AUTOMATIC ARCH SUPPORT FOR SHOES.

Application filed November 5, 1926. Serial No. 146,320.

The object of this invention, broadly stated, is to provide an automatic, built-in, flexible and elastic arch support for the shanks of shoes, the same being simple in character, positive yet flexible in its actions, automatic in operation, and which can be made and installed at a comparatively low price without materially adding to the cost of the production of shoes.

More specifically stated my object is to provide an elastic element located in connection with the shank of a shoe, the same to be installed under tension such as to cause the shank of the shoe to assume the shape of an arch which will yield to the pressure of one's foot but still contact the inner face of the shank of the shoe with the arch of the wearer's foot, thereby affording a firm yet flexible support for the foot, which support will automatically adjust itself to all parts of the arch of one's foot and will at all times exert pressure thereon regardless of the position of the foot.

Other particular objects and advantages of this invention will suggest themselves in the course of the following description.

The preferred means for carrying out the objects and principles of my invention in a practical manner is shown in the accompanying drawings, in which—Figure 1 is a bottom or underside plan view of a portion of a shoe, the outer sole being omitted, showing my invention secured in operative position. Figure 2 is a cross section of a portion of a shoe showing my invention in position, taken as on the line 2—2 of Fig. 1, but showing the outer sole of the shoe in position. And Figure 3 is a side elevation of a shoe in which my invention is incorporated, showing the position the shoe would normally assume on account of my invention.

Similar indices denote like parts in the several views.

In order that the invention and its connection with a shoe may be more fully understood and appreciated, I will now take up a detailed description thereof, in which I will set forth the same as fully and as comprehensively as I may.

In the drawings letter A denotes the outer sole of a shoe. B denotes the inner sole. C denotes the shoe upper, and D denotes the heel. All of said parts are of usual construction and I make no claim thereto, as they may be of various shapes, styles, and sizes.

The invention proper comprises a length of comparatively heavy and highly elastic material, such as elastic rubber which, for convenience of description, I will designate a rubber tongue 1. The said tongue 1 is of 60 a width somewhat less than the width of the inner sole B, and it is of such length as to extend from the heel, over the shank of the shoe, to the forward part of the sole, as shown in Fig. 1.

Said tongue is secured to the heel portion D and to the inner sole B, or rather between the inner sole B and the outer sole A, a short distance to the rear of the forward part of the heel D.

The attachment of the tongue 1 at the rear is by means of nails 2, or otherwise. The forward end of the tongue 1 is likewise secured by nails 3, or otherwise, to the inner sole B and to the outer sole A, where it lies 70 therebetween. However, before being secured at its forward end, the tongue 1 is to be stretched, that is brought to considerable tension, whereby the ends of the tongue will at all times, after being secured, be 80 inclined to move toward each other.

The tension thus attained is such that when the shoe is completed that it will cause the shank portion of both the inner and the outer sole to arch, as indicated at 4 in Fig. 85 3, thereby causing the shoe to normally assume approximately the shape shown in Fig. 3.

Numerical 5 denotes a fabric pocket, open at each end, in which pocket the tongue 1 90 is located and in which it is adapted to expand and contract. The edges of said pocket are secured to the inner sole by means of stitching, 6 and 7. Said pocket provides for the movements of the tongue 1 as it expands 95 or contracts. In order to cause the tongue 1 to expand and contract more freely in said pocket, a small quantity of graphite or talcum powder may be sifted into the pocket 5.

When constructed as above set forth it is 100 evident that I provide a built-in arch support which will not hurt one's foot, as it will fit the arch thereof, and adjust itself to the various movements of the foot, and also act as a cushion, and at all times tend to restore 105 or preserve the natural arch of one's foot. The process of installing my invention is quite simple, and it can be done as the shoe is being built, or it can be installed in the shoe after the shoe is built, by simply remov- 110

ing the outer sole and the heel, then attaching my device as set forth and then restoring the outer sole and the heel to their original positions.

5 I desire that it be understood that various changes may be made in the several details of the construction herein set forth without departing from the spirit of the invention and without sacrificing any of the advantages thereof which are new and useful.

Having now fully shown and described my invention, what I claim, and desire to secure by Letters Patent of the United States, is—

10 An arch support, comprising in combina-

tion with the inner and outer soles of a shoe, 15 an elastic tongue located between the inner and outer soles and extending across the shank of the shoe, means for securing the ends of the tongue under tension to the soles so as to cause the shank of the shoe to be 20 normally arched to support the arch of the foot, and a pocket member secured between the soles through which the elastic tongue extends.

In testimony whereof I have hereunto 25 subscribed my name to this specification.

HORACE C. MAYERS.
